UNITED STATES PATENT OFFICE.

CARLTON W. CANFIELD, OF WINTHROP, MINNESOTA.

PUMP.

SPECIFICATION forming part of Letters Patent No. 442,103, dated December 9, 1890.

Application filed May 7, 1890. Serial No. 350,891. (No model.)

To all whom it may concern:

Be it known that I, CARLTON W. CANFIELD, a citizen of the United States, residing at Winthrop, in the county of Sibley and State 5 of Minnesota, have invented certain new and useful Improvements in Pumps, of which the following is a specification.

My invention relates to pumps; and it consists in various features and details, herein-
o after set forth and claimed.

In the drawings, Figure 1 is a vertical sec-
tional view of my improved pump, and Fig.
2 a detail view.

A indicates the platform; B, the base-plate;
5 C, the standard, and D the discharge-pipe, the
standard and discharge-pipe passing down-
ward through the base-plate and platform,
where they screw into the coupling-piece or
connection E. The base-plate is flanged
o around the openings through which the pipes
C D pass to receive set-screws a, by means of
which the pipes are held in their proper ad-
justed positions. A brace F extends from
the standard to the discharge-pipe, while a
5 second brace F' extends from the standard
to the platform.

Fitting upon the upper end of the stand-
ard C is a cap G, having a perforated flange
or flanges b, to which is pivoted a loop or eye
35 c, to which the lever or handle H is adjust-
ably secured by a set-screw d, as shown in
Fig. 1.

By making the lever or handle adjustable
through or relatively to its eye or loop and
35 providing the flange on the cap with a series
of perforations I secure a greater range of
adjustment than has heretofore been secured.

Passing vertically through the discharge-
pipe D is a rod e, carrying at one end a hand-
40 wheel f and at the other end a ball or valve
plug g, as shown in Fig. 1, and in line with
the rod or stem e the coupling E is provided
with a discharge-outlet h, through which wa-
ter is passed when the ball or plug is to its
45 seat. At a point between its ends the coup-

ling-section E is provided with two openings
i and j in line with each other, the lower
opening i being the inlet, and surrounding
each of these openings is a flange or collar k.
Screwing into the upper collar k is a packing- 50
gland l, which is carried at the lower end of a
tube or sleeve I, the said tube or sleeve hav-
ing at its upper end an angular head or col-
lar m, by which it may be turned, while it is
connected at its lower end to the packing- 55
gland by means of a set-screw n, as shown
in both figures. Passing through the sleeve
or tube I is the pump-rod J, which, as shown
in Fig. 1, is connected at its upper end with
a rod or link o, which latter is in turn con- 60
nected to an adjustable eye or loop p, held in
place upon the handle or lever by a set-
screw q.

Now when it is desired to adjust the pack-
ing around the piston-rod J, it is not neces- 65
sary to dismantle the various parts or to de-
scend into the well, but merely to turn the
sleeve or tube I and with it the gland l.

The pump herein shown and described is
cheap, simple, and strong, and will be found 70
to wear well. The tube I provides the stay-
ing or bracing of the rod J. It also provides
the carrying of oil to the packing-gland l. By
this means the gland can be kept well oiled
from above, thereby giving the packing in- 75
definite duration over any other.

Having thus described my invention, what
I claim is—

In a pump, the combination, with the coup-
ling-section E, having a collar k, of the tube 80
I, having at its upper end an angular head
and at its lower end a packing-gland, and a
piston-rod passing through the tube.

In witness whereof I hereunto set my hand
in the presence of two witnesses.

CARLTON W. CANFIELD.
